(57) **CLAIM**

The ornamental design for a cladding of cladding components made out of a disposed tire, as shown.

DESCRIPTION

FIG. 1 shows a front perspective view of a cladding of cladding components made out of a disposed tire showing my new design;

FIG. 2 shows a front view thereof;

FIG. 3 shows a rear view thereof;

FIG. 4 shows a left side view thereof;

FIG. 5 shows a right side view thereof;

FIG. 6 shows a top view thereof; and,

FIG. 7 shows a bottom view thereof.

The broken lines are for illustrative purposes only and form no part of the claimed design.
